MOLD FOR CONCRETE STAIRWAY RUNNERS

Emil J. Johnson, Minneapolis, Minn.

Application November 23, 1951, Serial No. 257,829

5 Claims. (Cl. 25—118)

This invention relates to new and useful improvements in molds for making concrete stairway runners, and more particularly to such a device which is readily adjustable to vary the width of the stair tread.

An important feature of the present invention resides in the unique formation of the mold which comprises a bedplate upon which the various mold parts are adjustably secured, whereby runners of different sizes and angles may readily be formed on the same mold by slightly shifting the positions of the mold forming parts on said plate.

A further object is to provide a dual mold comprising a bedplate having a plurality of tread-and-riser forming elements adjustably secured thereto along the central portion of said plate, and wall forming members being secured to said plate adjacent the side edges thereof to form the bottom edges of the runners, and a pair of angle bars being positioned on said tread-and-riser forming elements and cooperating with the bedplate and said tread-and-riser elements to form the stepped upper edges of the runners, the upright webs of said angle bars cooperating with said wall members to form the lower portions of the runners, and whereby said lower portions will be relatively thicker than the stepped upper edge portions of the runners, thereby to reinforce the runners.

Other objects of the invention reside in the formation of the means for forming the ends of the runners, which are in the form of angle plates having means whereby they may be detachably secured to the upright webs of said angle bars, and in the simple means provided for adjustably securing the tread-and-riser elements to the bedplate, whereby they may readily be adjusted relative to one another to vary the width of the tread portions of the runners; in the provision of such an apparatus having dual mold cavities whereby two like runners may be molded in one operation; and in the simple and inexpensive construction of the mold whereby it may be manufactured in quantity production at very low cost.

These and other objects of the invention and the means for their attainment will be more apparent from the following description taken in connection with the accompanying drawings.

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is a plan or top view of the improved mold herein disclosed, showing it arranged for a four-step runner, and also showing the dual mold cavities whereby two left-hand runners may be poured at a time, such as shown in Figure 9;

Figure 2 is a perspective view of one of the tread-and-riser elements removed from the mold;

Figure 3 is a view showing the relationship between adjacent tread-and-riser elements and the means whereby the width of the tread portions of the runner may be varied in width;

Figure 4 is a view on the line 4—4 of Figure 3, with the upper element removed;

Figure 5 is a cross sectional view on the lines 5—5 of Figure 1, showing the various parts of the mold secured to the bedplate;

Figure 6 is a view similar to Figure 5 showing the dual mold cavities filled with concrete;

2

Figure 7 is a fragmentary view on the line 7—7 of Figure 1;

Figure 8 is a cross-sectional view on the line 8—8 of Figure 1 showing the means for securing the angle bars and the tread-and-riser elements to the bedplate;

Figure 9 is a perspective view of a left-hand runner when facing the runner;

Figure 10 is a front edge view of Figure 9;

Figure 11 is an outside view of the runner shown in Figure 9;

Figure 12 is a view similar to Figure 1, but showing the parts of the mold arranged for making two right-hand runners, such as shown in Figure 13;

Figure 13 is a view similar to Figure 9, but showing a right-hand runner;

Figure 14 is a front edge view of Figure 13; and

Figure 15 is an enlarged detail sectional view on the line 15—15 of Figure 3;

The novel mold herein disclosed is shown comprising a bedplate 2 which, for convenience, may be supported on suitable supporting rails or beams 3, as illustrated in Figures 5, 6 and 8. The bedplate is preferably rectangular in configuration, as shown in Figure 1. When the mold is to be utilized for making dual treads of like formation, elongated wall members 4 are secured to the marginal side edge portions thereof, which are adapted to form the bottom edges 5 of the runners, as shown in Figure 11. Each wall member 4 is shown having a base flange 6 seated upon the bedplate 2 and secured thereto by suitable bolts 7;

An important feature of the invention resides in the novel construction of the means provided for forming the tread and riser portions 8 and 9, respectively, of each runner, generally designated by the numeral 11. The tread-and-riser forming elements, generally designated by the numeral 12, are best illustrated in Figures 2, 3 and 4. Each such element comprises an elongated central portion 13 having oppositely disposed right angle portions 14 and 15 at its ends, as illustrated in Figures 2 and 3. The elongated central portion 13 of each element 12 is shaped cross-sectionally, as shown in Figure 15, wherein it will be noted that elongated semi-circular beads or ribs 10 are formed on the top and bottom sides of the central portion 13 of each element 12.

These semi-circular beads or ribs are adapted to form the mortar receiving grooves 20 in the tread portions of the runners, as shown in Figures 9 and 13. The right angle end portions 14 and 15 of each element are provided with similar beads or ribs 16 and 17, respectively, which form the vertical grooves 18 in the risers.

Each tread-and-riser forming element is also shown provided with plate portions 19 and 21 located in the median plane thereof and extending inwardly from each end of said element, as shown in Figure 2. These plate portions are adapted to be engaged by clamping plates 22 and 23 secured together by bolts or studs 24, as shown in Figures 5 and 6, thereby to adjustably secure together adjacent tread-and-riser forming elements 12, as will be understood by reference to Figures 1, 5 and 6.

To facilitate the positioning of the clamping plates 22 and 23, the studs 24 are preferably welded to the lower clamping plates 23 whereby they become, in effect, integral parts thereof. By thus adjustably securing together the elements 12, they may readily be adjusted relative to one another in accordance to the width of the tread desired. It should also be noted that when the tread-and-riser forming elements are clamped together by the plate elements 22 and 23 and bolts 24, all of the elements utilized in a given length runner are secured together, as a unit, and the opposed sides of said unit will be identical in formation, whereby dual mold cavities A and B are provided in the mold, as best illustrated in Figures 5 and 6.

To complete the formation of the mold, a pair of angle bars 25 are shown having their relatively wider legs or flanges 26 seated on top of the tread-and-riser forming elements 12 and are secured in position thereon by clamping plates 27 and bolts 28. The bolts pass between the adjacent edges of the bars 25 and through apertures provided in the bedplate 2, as best illustrated in Figure 8. The upright legs 29 of angle bars 25 co-

operate with the upright wall members 4 to provide the lower portion of each mold cavity, which, it will be noted by reference to Figures 5 and 6, are relatively deeper than that portion of each cavity which forms the stepped upper edge portions of the runners, thereby to reinforce the lower portions of the runners, as will readily be understood by reference to Figures 9 and 13. Suitable spacer blocks 40 may be inserted between the end portions of the angle bars 25 and the bedplate to support said end portions, when the clamping bolts 28 are manipulated to secure the angle bars in position on the tread-and-riser elements 12, as indicated in dotted lines in Figures 1 and 12.

The upper edges of the wall member 4 and the leg 29 of each mold cavity are horizontally aligned and cooperate to provide the open top of a mold cavity. One end wall of each mold cavity is formed by a plate element 31 having a base flange 32 shown seated on the bedplate 2, and said end wall member also has a strap-like portion 33 at one end seated against the upright leg 29 of the adjacent angle bar 25, as shown at the ends of Figure 1. The strap-like portions 33 of the end wall members 31 may be secured to the legs 29 of their respective angle bars 25 by suitable C-clamps 38. The opposite ends of the mold cavities A and B are formed by end wall members 35, each having a base flange 36 and a strap-like portion 37 at one end. The strap-like portions of said end wall members are seated against the upright legs 29 of angle bars 25 and are secured thereto by conventional C-clamps 38. Similar end wall members 35, each having a base flange 36 and a strap element 37 are similarly secured to the upright legs 29 of the angle bars 25 by C-clamps 38.

In the use of the novel mold herein disclosed, the various parts thereof are assembled on the bedplate as shown in Figure 1, whereby two runner cavities A and B are provided which, it will be noted, are identical in configuration, whereby the two runners simultaneously formed in said cavities will be identical in shape and will correspond to the left-hand runner shown in Figure 9, which is designed for a stairway comprising four steps. If a longer stairway is to be constructed, additional tread-and-riser forming elements are utilized and, conversely, if a shorter stairway is to be produced, only four tread-and-riser elements are utilized in the formation of the mold.

From actual experience I have found that six inches is a good average height for most stairway risers, and I have therefore made no provision for varying the height of the risers for different stairways. Provision is made, however, for varying the width of the treads, whereby the angle α of the runners, when set up as shown in Figure 11, may be varied depending upon the pitch to be desired and the width of the treads. Such variation in the width of the treads may readily be accomplished by simply releasing the clamping elements 22, 23 and 27, and then longitudinally shifting the positions of the tread-and-riser elements relatively to one another until the desired tread width is obtained. This will vary angle α of the runners, as will readily be understood, but the combined riser height of the completed stairway will remain the same regardless of the width of its treads.

In Figure 12 it will be noted the positions of the tread-and-riser forming elements 12 have been reversed from the positions of said elements in Figure 1, whereby dual cavities are formed for making right-hand risers 30, such as illustrated in Figures 13 and 14.

From the foregoing, it will be noted that the novel mold herein disclosed may readily be adjusted to any desired tread width, and that by the interlocking or overlapping arrangement of the tread-and-riser forming elements 12, dual mold cavities are formed which are disposed adjacent to one another, whereby they may readily be filled with wet concrete. As hereinbefore stated, the upper edges of the longitudinal wall members 4 and 29 are horizontally aligned, as indicated by the broken line b—b, whereby a straightedge may readily be manipulated on said edges to level the wet concrete in the molds, as shown in Figure 6.

When the concrete has set sufficiently in the mold cavities to permit handling, the clamping plates 22, 23 and 27 are removed or released, whereupon the angle bars 25 may be detached, and thereafter the tread-and-riser forming elements 12 may readily be removed from the bedplate to free the concrete runners, which are then loosely supported on the bedplate.

The apparatus as a whole is extremely simple and inexpensive as it will be noted the tread-and-riser forming elements 12 are all identical in construction and, in like manner, the end wall members 31 are identical, and also the end wall members 35.

The novel mold herein disclosed, when used in conjunction with the step-forming mold illustrated in my Patent No. 2,558,615, granted June 26, 1951, makes it possible to manufacture stock concrete stairways in large quantities at very low cost. While the runners illustrated in Figures 9 and 13 are applicable for a four-step stairway, it is to be understood that the length of the runners may readily be varied by simply increasing or decreasing the number of tread-and-riser elements 12 used in the formation of the mold. In an installation requiring a rather long stairway, it may be found more desirable to use a plurality of stock or four-step runners, and arrange them in end-to-end relation to provide the required length stairway.

In such installations suitable abutments must be provided at the joints between adjacent runners to support and retain the runner sections of each composite runner in longitudinal alignment, and also to prevent displacement of the runner sections longitudinally and laterally. Such abutments may readily be made with wet concrete, when the stairway is used on an inclined bank or slope. If the stairway is to be embodied in a building structure, a suitable structural support may be erected for supporting the intermediate portions of the runners.

In some installations, it may also be found more desirable to make the runners of uniform thickness throughout their full width. This may readily be accomplished by eliminating the angle bars 25 and substituting relatively lower side walls for the wall members 4, shown in Figures 5, 6 and 8, the height of said substitute wall members being equal to the height of the tread-and-riser elements 12, as will be understood by reference to the drawings. Suitable means, not shown, is then provided for securing the elements 12 to the bedplate.

The foregoing detailed description has been given for clearness of understanding only, and no unnecessary limitations should be understood therefrom, but the appended claims should be construed as broadly as permissible in view of the prior art.

I claim as my invention:

1. A mold for making stairway runners each having an upper stepped edge and a lower longitudinal edge, a bedplate, a wall member secured to said bedplate adjacent one side edge thereof and extending at least the length of the runner to be made for forming the lower longitudinal edge of the runner, a plurality of angular tread-and-riser forming elements supported on the intermediate portion of said bedplate and disposed in angular relation to said wall member, said elements being disposed in offset relation to one another to form the tread portions of the runner, clamping elements engageable with said tread-and-riser forming elements to adjustably secure them in position on the bedplate, and an elongated member of right angular cross-section seated upon and secured to said tread-and-riser forming elements and constituting portions of the top wall of the mold, the bottom wall of said cavity being defined by the bedplate.

2. In a dual mold for forming concrete stairway runners, a fixed bedplate, opposed longitudinally extending wall members secured to said bedplate adjacent to the marginal side edges thereof and cooperating to form correspondingly upright walls of the mold cavities, a plurality of tread-and-riser forming elements adjustably secured to the bedplate between said wall members in angular relation thereto and disposed in offset relation to one another and cooperating to form the tread-and-riser forming wall portions of the mold cavities, said tread-and-riser forming elements being of like configuration and each comprising a central web disposed in the median plane of said elements, clamping bars engageable with the webs of adjacent tread-and-riser forming elements to adjustably secure them together and to the bedplate, a pair of longitudinally disposed angle bars seated on said tread-and-riser forming elements and forming portions of the top walls of the mold cavities, and end wall members detachably secured to said angle bars for defining the end walls of the mold cavities.

3. A mold according to claim 2, wherein the opposed

wall members and said tread-and-riser forming elements cooperate to provide two separate mold cavities.

4. In a mold for making concrete stairway runners, a bedplate, a member secured to the top surface of said bedplate and having an elongated wall surface extending outwardly from the bedplate to form an upright wall of the mold cavity, a plurality of angular tread-and-riser wall forming elements secured to the bedplate in angular spaced relation thereto and being disposed in offset relation to one another to form the tread-and-riser wall surfaces of the mold cavity, said tread-and-riser wall forming surfaces each having a longitudinal bead thereon located in the median plane of said wall surfaces adapted to form mortar receiving recesses in the tread-and-riser wall surfaces of the completed stairway runners, means for adjustably securing said tread-and-riser elements in position on the bedplate in accordance with the size of stairway runner to be made, and a member seated upon and secured to said tread-and-riser elements and forming a portion of the top wall of the mold cavity.

5. In a dual mold for forming concrete stairway runners, an elongated bedplate, opposed longitudinally extending wall members secured to said bedplate adjacent to the marginal side edges thereof and cooperating to form corresponding upright walls of the mold cavity, a plurality of tread-and-riser forming elements positioned on the bedplate between said wall members in angular relation thereto and disposed in offset relation to one

another and cooperating to form the tread-and-riser forming wall portions of the mold cavities, said tread-and-riser forming elements being of like configuration and each comprising a central web disposed in the median plane of said elements, clamping bars engageable with the webs of adjacent tread-and-riser forming elements to adjustably secure them together and to the bedplate, a pair of elongated members seated upon and secured to said tread-and-riser forming elements to form portions of the top walls of the mold cavities, a pair of end wall forming members detachably secured to said elongated members for defining the end walls of the mold cavities, said end wall forming members being disposed in right angular relation to one another, whereby one of said end wall forming members defines the bottom horizontal edge of each completed runner, and the other of said end wall forming members defines the vertical edge of the upper end of each runner.
